CLAIM

I claim, the ornamental design for an IV lock box, as shown and described.

DESCRIPTION

FIG. 1 is a first perspective view of an IV lock box; FIG. 2 is a second perspective view of the IV lock box of FIG. 1;

FIG. 3 is a first elevation view of the IV lock box of FIG. 1; FIG. 4 is a second elevation view of the IV lock box of FIG. 1;

FIG. 5 is a third elevation view of the IV lock box of FIG. 1; FIG. 6 is a fourth elevation view of the IV lock box of FIG. 1;

FIG. 7 is a top plan view of the IV lock box of FIG. 1; and, FIG. 8 is a bottom plan view of the IV lock box of FIG. 1. The broken lines in the drawings depict portions of an IV lock box that form no part of the claimed design.
